UNITED STATES PATENT OFFICE.

WILLIAM A. SORG, OF ST. PAUL, MINNESOTA.

LINE UNIT-CASE FOR PRINTING-MACHINES.

979,586.

Specification of Letters Patent. Patented Dec. 27, 1910.

Application filed September 21, 1908. Serial No. 454,011.

To all whom it may concern:

Be it known that I, WILLIAM A. SORG, a citizen of the United States, residing at St. Paul, in the county of Ramsey and State 5 of Minnesota, have invented a new and useful Improvement in Line Unit-Cases for Printing-Machines, of which the following is a specification.

My invention relates to improvements in 10 line cases for holding type in printing machines and has for its primary object a simple and inexpensive device which permits of re-adjustment of the type.

The primary advantages obtained by the 15 use of my invention are as follows:—A uniform pressure is applied upon the entire line when it is locked, so that there is no tendency for the spacers or justifiers used between letters and words to work up. It 20 is possible by means of my invention to leave the type loose in the line case so that more perfect imitation of type-writing may be obtained and it is also possible by means of this construction to hold the type in 25 their relative position and still allow them to have some movement. With the use of the line unit case any portion of the letter may be rearranged, changed and corrected without distributing the whole form, thus 30 making it possible to retain salutations, introductory passages or any part of the letter as it originally stood. The use of line cases employing my invention obviates all 35 possibility of spilling or pieing the type. It also makes it unnecessary for the operator to use a composing stick or other method of 40 setting up as each line unit case is a composing stick in itself. Distribution is made much easier by means of my invention as 45 the entire line is taken from the form and the type may be distributed without error. The life of the type is also increased by the use of my invention for each line of type and each type is protected by the case and 50 it is impossible for it to receive any shock or twisting strain that would cause it to break.

The above advantages apply more particularly to the line unit case employing my invention in connection with the special construction of type used therewith as the type which stand on their lower ends when in the form, have shoulders near the top from 55 which they hang when the line case is in the hands of the operator during removal

for corrections, transfer or distribution, thus preventing the spilling of the type.

In the accompanying drawings forming part of this specification, Figure 1 is a perspective view of my invention showing a line 60 of type set up in the unit case; Fig. 2 is a longitudinal central section in elevation of a detail portion of the unit case showing the type therein and Fig. 3 is a cross-sectional view of the line case with the type therein. 65

In the drawings A represents the line unit case which is composed of a pair of parallel and vertical plates 2 and 3 forming sides which are soldered, brazed or otherwise secured to a pair of end blocks 4 and 5 70 which hold said sides spaced apart.

B represents the type each of which is formed with a shank 6 and a pair of shoulders 7 and 8 at the upper end of said shank. The width of the shank is nearly equal to 75 the distance between the sides 2 and 3 of the line case while the width of each type including the shoulders 7 and 8 corresponds with the width of the line case including the sides. Preferably the shank depends 80 slightly below the lower edges of the sides when the type is placed in the line case causing the type to stand upon the bed of the printing machine when the line case is placed in the form and the form locked in 85 the machine. By causing the type to stand upon its lower ends in the printing machine, a better imitation of typewriting can be produced and by constructing the type with shoulders as described, the type can be 90 easily and quickly placed in a line case without danger of falling through. The locking up on the line case is by means of a set screw 9 passing longitudinally through the space block 4 the inner end of said screw 95 impinging against the type and holding it locked in the line case. It is evident that the lock up may be made by means of a wedge in the usual manner or by any other arrangement desired. The justifiers or 100 blanks 10 are constructed similar to the type, their shanks 6, however, need not be as long as the shanks on the type for there is no necessity of the justifiers standing upon the bed plate of the printing machine. 105

In use the line case is held by hand and the type including the justifiers placed therein by dropping them between the sides of the case. The shoulders 7 and 8 are caught upon the upper edges of the sides 110

and the type hang freely within the space between them. After the line case has been filled with type including justifiers as desired, the set screw is turned down tightly 5 against the type thus locking it in the case. Preferably the type is adjusted loosely in the case so that the type has limited trans- 10 verse play therein when locked up. By this construction more perfect imitation of type writing is produced by the type. It is also easier to set the type in the case.

In accordance with the patent statutes I have described the principles of operation of my invention together with apparatus 15 which I now consider to represent the best embodiment thereof but I desire to have it understood that the construction shown is only illustrative and that the invention can be carried out by other means and applied 20 to uses other than those above set forth within the scope of the following claims.

Having described my invention what I claim as new and desire to protect by Letters Patent is:

25 1. In means for printing, the combination of a line holder comprising side walls in parallel relation and spaced apart and forming a substantially vertical passageway between them, and a printing type having a 30 printing end and a plain or non-printing end to rest on a type bed, said type being of greater length than the height of the line holder and having a supporting shoulder adapted to engage the upper edge of one of 35 said walls to support the type therein with its printing end upward when not on the type bed and with the plain or non-printing end protruding from the lower edge of the line holder, whereby when said line holder 40 with the type therein is placed on the type bed with the non-printing end of the type against the bed, said shoulder is projected out of engagement with the wall of the line holder.

45 2. In means for printing, the combination of a line holder, comprising, side walls in substantially parallel, longitudinally and transversely and held together at their ends, a lock up in said holder, and a printing type 50 having a printing end and a plain or non-printing end to rest on a type bed, said type being of greater length than the height of the line holder and having a supporting shoulder adapted to engage the upper edge 55 of one of said walls to support the type therein with its printing end upward when

not on the type bed and with the plain or non-printing end protruding from the lower edge of the line holder, whereby when said line holder with the type therein is placed on the type bed with the non-printing end of the type against the bed, said shoulder is projected out of engagement with the wall of the line holder.

3. In means for printing, the combination 60 of a line holder, comprising, side walls in parallel relation and held spaced apart forming a substantially vertical passageway between them, and a printing type having a printing end and a plain or non-printing end to rest on a type bed and fitting loosely 70 between said walls, said type being of greater length than the height of the line holder, and having a supporting shoulder adapted to engage the upper edge of one 75 of said walls to support the type therein with its printing end upward when not on the type bed and with the plain or non-printing end protruding from the lower edge of the line holder, whereby when said line holder 80 with the type therein is placed on the type bed with the non-printing end of the type against the bed, said shoulder is freely projected out of engagement with the 85 wall of the line holder.

4. In means for printing, the combination 90 of a line holder comprising a pair of side walls parallel longitudinally and transversely and held together at their ends, and a printing type having a printing end and a plain or non-printing end to rest on a type bed, said type being of greater length than the height of the line holder, and having a supporting shoulder adapted to engage the upper edge of one of said walls to support 95 the type therein with its printing end upward when not on the type bed and with the plain or non-printing end protruding from the lower edge of the line holder, whereby when said line holder, with the type therein, is placed on the type bed, with 100 the non-printing end of the type against the bed said shoulder is projected out of engagement with the wall of the line holder.

In testimony whereof, I have signed my 105 name to this specification, in the presence of two subscribing witnesses.

WILLIAM A. SORG.
